CLAIM

The ornamental design for a rim of storage bucket lid, as shown and described.

DESCRIPTION

FIG. 1 is a top perspective view of a rim of a storage bucket lid;

FIG. 2 is a bottom perspective view thereof;

FIG. 3 is a top plan view thereof;

FIG. 4 is a bottom plan view thereof; and,

FIG. 5 is a front elevational view thereof.

The ornamental design which is claimed is shown in solid lines in the drawings. The broken lines in the drawings form no part of the claimed design. The dash dot broken lines shown in the drawings are for the purpose of illustrating a boundary line, which form no part of the claimed design. A rear elevational view, a left side elevation view, and a right side elevational view are not shown because it is identical to the front elevational view shown in FIG. 5.
